QUICK-ACTING C-CLAMP

Ernest C. Neal, Chicago, Ill., assignor of one-half
to Elmer Brandell, Chicago, Ill.

Application July 30, 1945, Serial No. 607,781

3 Claims. (Cl. 144—305)

1

This invention relates to a clamp commonly called a C clamp.

An important object of the present invention is to provide a clamp of new and improved construction whereby a slidably movable clamping jaw is adapted to be brought into clamping engagement with a cooperating jaw and then locked in position, further clamping of the slidably movable jaw being effected by a rotary movement.

Another important object of the invention resides in a spring pressed self-locking holding member pivotally supported by the body of a C clamp and having locking engagement with a slidably locking clamping end or jaw so as to permit free and ready movement in a closing position of said jaw but to lock normally the jaw in a reverse direction.

Other important objects of the invention reside in the construction, arrangement and location of the parts to provide a C clamp of improved construction to effect quick and easy clamping of an article between a fixed jaw and a cooperating movable jaw.

Numerous other objects and advantages will be apparent throughout the progress of the following specification.

The accompanying drawings illustrate a selected embodiment of the invention and the views therein are as follows:

Fig. 1 is a detail side elevational view of an improved C clamp and embodying the invention, parts being broken away for the sake of clearness;

Fig. 2 is an elevational view of the improved C clamp showing the slidably mounted jaw pushed down into contact with a workpiece and locked in such position by the holding member;

Fig. 3 is a view similar to Fig. 2 but shows the slidable portion of the C clamp screwed part way out of its cooperating sleeve to effect tighter clamping engagement with the workpiece;

Fig. 4 is a detail perspective view of the friction lock or sleeve lock;

Fig. 5 is a detail elevational view showing a spring arranged to effect quick release of the movable jaw;

Fig. 6 is a detail elevational view of a modified form of C clamp and embodying the invention, parts being broken away for the sake of clearness;

Fig. 7 is a view similar to Fig. 6 but showing the jaws of the clamping member in clamping engagement with the workpiece; and

Fig. 8 is a detail sectional view on the line 8—8 of Fig. 6.

The particular C clamp herein shown for the purpose of illustrating the invention comprises the usual C frame 1 provided with a flattened member or jaw 2. A second clamping member or jaw 3 comprises a head 4 which has swivel engagement with a bar or rod 5. The bar or rod 5 is received inside of an outer sleeve or tube 6. This rod or bar 5 is provided with screw threads 7 which are adapted to have threaded engagement with internal threads 8 formed in the inside of the tube or sleeve 6.

The tube or sleeve 6 is adapted to have slidable movement in an elongated boss 9 formed in the upper end of the C frame 1.

The upper end of the rod or bar 5, which is circular in cross section, is provided with a knob 10 rigidly secured thereto. A handle operating member 11 cooperates with the head or knob 10 to provide greater leverage for the rotation of the rod or bar 5. The handle 11 may have slidable engagement in the head 10 or it may be fixed thereto if desired.

A free floating member or friction collar 12, Fig. 4, is provided with bifurcated legs 13 for attachment to the body of the C frame. Each of the legs 13 is provided with an elongated slot 14, through which a pin 15 passes to secure the friction collar 12 to the C frame. The legs 13 project upwardly from the normal flat plane 16 of the main body of the friction collar 12. The body of the friction collar 12 is provided with an opening 17 therethrough to receive the tubular sleeve 6. The edges of the opening 17 are cut back as indicated at 18, 19 to provide bights for biting into the exterior surface to hold the tube 6 in its adjusted position. The friction collar 12 is loosely secured to the C frame 1 by means of the slot and pin connection 14, 15. The elongated slots 14 prevent binding of the friction collar 12 during operation of the device.

A transverse rib 20 is formed on the upper face of the friction collar 12, Fig. 4, so as to provide a stop to limit the upward pivotal movement of the friction collar on the C frame 1. The end of the friction collar 12 terminates in an extension or finger piece 21 to permit manual manipulation of the free floating friction collar to unlock the tubular sleeve 6 from the locking or biting parts 19 surrounding the hole 17.

A screw 22 passes through a hole 23 in the free floating friction collar 12 and preferably has threaded engagement with a part of the C frame as clearly shown in Fig. 1. This screw limits the vertical pivotal movement of the friction collar 12 on its pivot 15, the upward movement of the

friction collar 12 being limited by the rib 20 and the downward movement of the friction collar being limited by the head of the screw 22.

A coil spring 24 surrounds the screw 22 and is preferably recessed into the collar 12, as indicated at 25, Fig. 1. The screw 22 has threaded engagement at its end with the C frame, the rest of the body of the screw being smooth and acting as a guide pin.

The free floating friction collar 12, therefore, permits free slidable movement of the tubular sleeve 6 in a downward direction, but prevents upward movement of the sleeve 6 unless the finger piece 21 is operated to release the biting edges 19 from the tube. When the finger piece 21 is depressed, free sliding upward movement of the tubular sleeve 6 is permitted.

Operation

The work, or workpiece, is adapted to be clamped or locked between the surfaces of the jaw 2 and the head 4. The C clamp is first positioned, as shown in Fig. 1, with the member or jaw 2 engaging beneath the workpiece. The tubular member 6 is then pushed downwardly, such as by applying pressure on the knob 10, whereupon the surface 4 of the jaw 3 will come into engagement with the upper side of the work, or workpiece, as clearly shown in Fig. 2, whereupon the work, or workpiece, for most conventional purposes, is securely held between the upper and lower jaws.

In some instances, however, the slideable movement of the jaw 3 against the workpiece is insufficient for obtaining a tight clamp. Therefore, the handle 11 is given a part rotation so that the threaded bar 5 will be turned and, consequently, extend through a predetermined distance beyond the lower end of the sleeve 6. The rotating of the screw 5, therefore, provides additional clamping pressure against the workpiece, as shown in Fig. 3. Usually, a part turn of the screw member 5 is sufficient to lock the workpiece tightly and firmly between the jaws 2 and 3. When it is desired to release the workpiece, the finger piece 21 of the friction collar is depressed, whereupon the biting engagement surrounding the opening 17 is released from the tube 6, and the tube may be easily and quickly returned to inoperative position, as shown in Fig. 1.

A coil spring 26, Fig. 5, may be interposed between the upper end 27 of the C frame and the lower edge of a collar 28 so that when the finger piece 21 is released, the spring 26 normally will cause the tube 6 to rise a predetermined distance and, therefore, automatically release the workpiece between the clamping jaws.

A modified construction, shown in Figs. 6 to 8, inclusive, comprises a handle member 30 pivotally mounted as at 31 to a nonthreaded smooth bar or rod 32, which bar or rod 32 is slidably mounted in the tubular sleeve 6. The handle 30 is provided with a cam end 33 which is adapted to cooperate with the upper surface of a collar member 34 so as to provide additional locking means.

In the modification shown in Figs. 6 to 8, inclusive, the tubular sleeve 6 is moved freely downwardly until the movable jaw 3 is brought into clamping position with respect to the lower jaw 2 to clamp the workpiece between the jaws 2 and 3. After the initial engagement or locking of the workpiece between the jaws 2 and 3, the lever or handle 30 is operated so as to move the tube downwardly a predetermined distance to provide for additional effective locking of the piece be-

tween the jaws. If desired, the tube 6 may have mounted therein a spring 35 which is arranged between a shoulder 36 on the tube and under a shoulder 37 on the rod 32 so as to effect an automatic release of the workpiece and retract the jaw 3 away from the workpiece when the finger piece 38 on a modified form of friction collar 39 is depressed.

The modified friction collar 39 consists of a body 40 which is mounted between a strip 41 secured to the body of the C frame and a pivot bearing 42, the pivot bearing 42 riding in a shallow curved recess 43, as clearly shown in Fig. 6. A spring 44 may be interposed between an underside of the friction collar 39 and the upper surface of the strip 41, the spring 44 being preferably recessed partly within the friction collar 39, as indicated at 45.

The operation of the device shown in Figs. 6 to 8, inclusive, consists in pressing the tube 6 downwardly until the jaw 3 is in engagement with the workpiece, whereupon the sleeve will be locked by the locking member 39. The handle 30 is then raised from the position shown in Fig. 6 to the position shown in Fig. 7, whereupon an additional locking or tightening movement is given or provided.

Depression of the finger piece 38 of the friction collar 39 permits release of the workpiece and permits the tube 6 to be slid upwardly in the opening provided in the friction collar 39, the opening in the friction collar 39 being identical with the opening 17 in the friction collar 12. The spring 35 assists in raising the tubular sleeve 6 a predetermined distance when the finger piece 38 is depressed. The spring 32 may be arranged between shoulders 36 and 37, as shown in Fig. 6, or the spring 35 may be arranged as shown in Fig. 8, Fig. 8 showing the spring completely housed within an enlarged end of the tubular sleeve 6.

The invention provides a clamp which may be quickly operated to bring the clamping jaws into quick clamping position and then permits a tightening action to take effect by the operation of a handle, whether the device be made in accordance with the construction shown in Figs. 1 to 5, inclusive, or whether the device be made in accordance with the modified construction shown in Figs. 6 to 8, inclusive.

The device is strong and durable in construction, is efficient in operation, and may be readily and economically manufactured.

Changes may be made in the form, construction and arrangement of the parts without departing from the spirit of the invention or sacrificing any of the advantages thereof, and the right is hereby reserved to make all such changes as fairly fall within the scope of the following claims.

The invention is hereby claimed as follows:

1. A clamp embodying a body forming a yoke, a stationary jaw at one end of the yoke, a bearing at the other end of the yoke, a sleeve slidably mounted in said bearing, a rod within the sleeve, movable with the sleeve and with respect to the sleeve in directions lengthwise thereof, a jaw carried by one end of said rod beyond the sleeve, for co-operation with the first said jaw, a locking member disposed within the yoke adjacent said bearing and having an opening in alignment with the opening in the bearing, and through which opening said sleeve passes, means for adjusting the rod with respect to the sleeve to force the jaw on the rod toward the other jaw, means loosely connecting one end of the locking member to the body of the clamp, a hand-

engaging portion on the other end of the locking member, a guide secured to the clamp body and passing loosely through the locking member, resilient means encompassing said guide and tending normally to move the locking member in one direction, to grip the sleeve, said guide and resilient means being disposed within the clamp adjacent one of the yoke arms, and means tending normally to move said sleeve and rod through the said bearing, to move the jaw on the rod away from the jaw on the yoke arm. 10

2. A clamp embodying a body forming a yoke, a stationary jaw at one end of the yoke, a bearing at the other end of the yoke, a sleeve slidably mounted in said bearing, a rod within the sleeve, 15 movable with the sleeve and with respect to the sleeve in directions lengthwise thereof, a jaw carried by one end of said rod beyond the sleeve, for co-operating with the first said jaw, a locking member disposed within the yoke adjacent said bearing and having an opening in alignment with the opening in the bearing, and through which opening said sleeve passes, means for adjusting the rod with respect to the sleeve to force the jaw on the rod toward the other jaw, means 20 loosely connecting one end of the locking member to the body of the clamp, a hand-engaging portion on the other end of the locking member, guide means secured to the clamp body and loosely associated with the locking member, resilient means mounted on said guide means and supported thereby tending normally to move the locking member in one direction to grip the sleeve, 25 said resilient means being mounted within a recess in said locking member, and said locking member and guide means being disposed within the clamp adjacent one of the yoke arms, and resilient means tending normally to move the rod through the bearing, to move the jaw on the rod away from the jaw on the yoke. 40

3. A clamp comprising a yoke having a sta-

tionary jaw at one end thereof, a bearing at the other end of said yoke, a sleeve slidably mounted in said bearing, a rod within the sleeve, movable with the sleeve and with respect to the sleeve lengthwise thereof, a jaw carried on one end of the rod for cooperation with the stationary jaw, means for moving the rod with respect to the sleeve to force the jaws together, a locking member disposed within the yoke adjacent the underside of said bearing having an opening in alignment with the opening in the bearing and through which opening the sleeve passes, said locking member having a hand engaging portion at one end and an arcuate recess at the opposite end thereof, a cylindrical pin loosely fitted into said arcuate recess and resting against the underside of said yoke to provide a loose pivot for said locking member, a guide bracket mounted on said yoke adjacent the bearing and passing loosely around said locking member, and resilient means supported by said bracket and mounted substantially within said locking member and tending normally to move the locking member in one direction, to grip the sleeve. 25
